DISPLAY RACK

Claude Edward Smith, Forest Grove, Oreg.

Application August 7, 1933, Serial No. 684,055

2 Claims. (Cl. 211—45)

This invention relates to a novel display rack which is especially but not necessarily, adapted to support and conveniently display a plurality of different grades of patterns of small scatter 5 rugs.

The rack is particularly designed to accommodate and conveniently show so-called small scatter rugs constructed of linoleum, congoleum and equivalent relatively stiff self sustaining types.

10 So far as has been ascertained rugs of this variety are stacked and otherwise piled in rather haphazard manners and handled in a wear producing disorderly way by salesmen and customers. Therefore I have discovered and constructed what I believe to be a revelation in this line of endeavor in that it embodies ingenious features carefully selected and operatively fitted in place to provide for logical and systematic display and handling purposes, and in accomplishing this result I have perfected an arrangement 15 thought to be new because of its ability to accommodate eight or more different groups of rugs conveniently sub-divided and displayed for expeditious selection and sale purposes.

20 Other features and advantages will become more readily apparent from the following description and drawings.

In the drawings:

Figure 1 is a top plan view of a rack constructed 25 in accordance with the principles of the present invention.

Figure 2 is an elevational view thereof.

Figure 3 is a view in section end elevation disclosing the assemblage of parts more in detail.

30 As shown in particular in Figure 3 the structure is characterized by an openwork arrangement of parts which may be distinguished as including four vertical uprights 4 secured to and rising from a base frame 5. The frame 5 is provided with transporting and turning casters 6. The uprights 4 are partly maintained in assembled relationship through the instrumentality of appropriate braces 7. The numeral 8 designates a snug fitting relatively small top frame. The 35 numeral 9 designates an intermediate frame somewhat of the same proportion as the base frame 5 and located at about the center of the uprights 4. The racks are divided in two distinguishable groups, namely the upper rigidly mounted racks 10 and the lower hingedly mounted racks 11. These racks 10 are in the form of vertically elongated boxes 12 nailed or otherwise secured as at 13 to the uppermost frame 8 and inclining downwardly and resting against 40 the intermediate stabilizing frame 9. These

boxes as well as the lower boxes are identical in construction and include the tapered side walls and are open at their upper ends to accommodate the easily removable relatively stiff individual scatter rugs 14. The lower boxes or racks 60 are secured to arms or strips 15 which are in turn hingedly connected as at 16 to the lower frame. The upper open ends of these racks which incline inwardly bear against what may be designated and distinguished as an abutment frame 65 17. As shown in dotted lines the lower box like rack 11 may be swung out to the positions illustrated and clear of the lower ends of the upper boxes to facilitate placement and removal of 70 rugs.

Briefly considered I have evolved and produced a portable roller equipped structure embodying uprights provided with a group of four distinguishable frames namely the base frame 5 on roller 6, the top supporting frame 8 for the upper 75 racks 10 and the intermediate retention frame 9 for the lower end portions of said racks 10. Then just beneath the frame 9 is what is designated and distinguished as the abutment frame 17, this being a rest or sustaining device for the upper 80 swingable end of hingedly mounted boxes or racks 11. With this arrangement I provide upper and lower sets of boxes the upper ones being rigidly mounted and inclined to a convenient display 85 position and the lower ones normally maintained in an inclined state and hingedly mounted in place in such a way as to permit the upper ends to be swung outwardly for convenient placement and removal of the rugs.

It is thought that a multiple type rack of this 90 form is characterized by simplicity and convenience and embodies features of accommodation and adaptation which transcend those of similar arrangement. Hence it is particularly well fitted, correctly balanced and mechanically made to fulfill the requirements of a structure of this class.

A careful consideration of the foregoing description in conjunction with the illustrative drawings will enable the reader to obtain a clear 100 understanding of the purpose, features and advantages, the explicit construction, and the invention as hereinafter claimed.

It is to be understood that minor changes in shape, size, relative proportions, and materials may be resorted to in practice without departing 105 from the spirit of the invention or the scope of the invention as now claimed.

Having thus described my invention, what I claim as new is:

1. A rug display device comprising a support, 110

a plurality of individual rug reception and retention racks, each rack being in the form of a vertically elongated box closed at its lower end, open at its upper end and provided with walls receding 5 in width dimension toward the upper open end, said racks being arranged in upper and lower groups on the support, and each group embodying a set of four distinguishable racks for convenient selection and display purposes, the lower racks 10 being hingedly mounted on the support, the upper racks being rigidly mounted on the support.

2. In a structure of the class described, a base frame, a plurality of uprights attached to and rising therefrom, the uprights being arranged in 15 horizontally spaced relation to provide a support-

ing structure of general rectangular form in cross sectional shape, a relatively small frame attached to and surrounding the upper end portions of said uprights, an intermediate frame attached to and surrounding the intermediate portions of the uprights disposed in superposed relation above the base frame, a plurality of open ended box like rugs supporting racks arranged in upper and lower groups, the upper racks being attached to and depending from said upper frame and resting at their lower ends on the intermediate frame, the lower racks being hingedly attached to the base frame and having their upper ends swingable outwardly.
